CLAIM

The ornamental design for a linear actuator accessory, as shown and described.

DESCRIPTION

FIG. 1 is a perspective top view of my new and ornamental design for a linear actuator accessory,

FIG. 2 is a perspective bottom view thereof,

FIG. 3 is a top plan view thereof,

FIG. 4 is an elevational right side view thereof,

FIG. 5 is a bottom plan view thereof,

FIG. 6 is an elevational rear view thereof,

FIG. 7 is an elevational front view thereof; and,

FIG. 8 is an elevational left side view thereof.
